US0D1109644S

(12) **United States Design Patent** (10) Patent No.: **US D1,109,644 S**
(45) Date of Patent: ** Jan. 20, 2026

(54) **MOTORCYCLE**

(71) Applicant: **LAND ENERGY, INC**, Cleveland, OH (US)

(72) Inventors: **Evan Painter**, Cleveland, OH (US); **Zack Simmering**, Mansfield, OH (US); **George Henry Remington**, Bay Village, OH (US); **Scott Colosimo**, Cleveland, OH (US)

(73) Assignee: **LAND ENERGY, INC**, Cleveland, OH (US)

(**) Term: **15 Years**

(21) Appl. No.: **29/866,370**

(22) Filed: **Sep. 9, 2022**

(51) LOC (15) Cl. **12-11**

(52) U.S. Cl.

USPC **D12/107**

(58) **Field of Classification Search**

USPC D12/107, 1, 82, 85, 86, 88, 108-113; D21/424, 432, 433, 434, 538

CPC B62K 11/00; B62K 11/02
